UNITED STATES PATENT OFFICE.

HERMANN BERNHARD FELDMANN, OF PHILADELPHIA, PENNSYLVANIA,
ASSIGNOR TO JOSEPH R. TASKER, OF SAME PLACE.

PULVERIZING-MACHINE.

SPECIFICATION forming part of Letters Patent No. 290,874, dated December 25, 1883.

Application filed July 16, 1883. (No model.)

To all whom it may concern:

Be it known that I, HERMANN BERNHARD FELDMANN, of the city and county of Philadelphia, and State of Pennsylvania, have invented certain Improvements in Pulverizing-Machines, of which the following is a specification.

My invention, broadly considered, relates to and embodies improvements upon a certain novel pulverizing-machine invented by William Henry Thompson, of Islington, county of Middlesex, Kingdom of Great Britain, and patented to him in and by Letters Patent of the United States No. 249,489, dated November 15, 1881, to which Letters Patent reference is to be made for a more clear comprehension of my present improvements.

It also relates to and embodies improvements upon certain patented inventions which are improvements upon the Thompson machine, and are hereinafter mentioned.

In view of the above fact, and in order to a better comprehension of my present invention, I regard it as necessary to briefly describe the several inventions upon which my present is an improvement.

Broadly stated, Thompson's invention consists in the combination, within a suitable inclosing-case embodying in its own structure a vertically-erected hollow circular track, of an independent sphere or ball adapted to revolve around the casing, and of giving means for imparting to the ball not only revolution around the casing-track, but also rotation about its own axis. In the Thompson machine, as also in mine, material to be pulverized is fed through a hopper into the casing, and is crushed by the combined revolution and rotation of the sphere or ball. The means employed by Thompson for effecting the combined movement of the ball are a pair of vertically-erected disks provided with peripheral beveled bearing-surfaces, and arranged face to face at some distance on either side of the center of a shaft horizontally journaled through the casing, and by which they are revolved.

The disks are capable of rocking movements by virtue of being each loosely hung or supported on the shaft between two collars having curved bearing-faces. The collars prevent

a lateral movement of the disks at their center. The operation of the disks and ball is described by Thompson in the following language, which also I regard as of importance to restate here, in order that a more thorough comprehension of my improvements may be had. Thompson says: "The operation of the disks and ball is substantially as follows: When the disks are revolved, their tendency is to assume a position exactly at right angles to the shaft; but as they cannot do this for the reason that the diameter of the ball at the point of contact exceeds the distance between the adjacent bearing-faces, it follows that they bear or press upon the ball in their effort to assume this position, and crowd the latter against the casing with greater or less force, according to the rapidity of the revolution. The disks, also, by the friction of the contact, carry the ball with them in their revolution about the casing, and thus communicate to it a centrifugal action. The ball, then, it will be understood, is caused to act upon the material to be pulverized with a resultant force, which is obtained from three distinct sources, as follows: first, the direct radial thrust which is received from the efforts of the disks to assume a position at right angles to the shaft, the bearing-faces of the same acting as inclined planes to crowd the ball against the inner surface of the casing; second, the centrifugal action which results from the rapid revolution of the ball around the casing; and, third, the grinding action which results from the rotation of the ball upon its axis. By adapting the disks to rock upon the shaft the ball is permitted to move on radial lines to and from the shaft, according to the amount of material in the casing, without being free at any time from the action of the disks."

My invention also relates to and embodies in its structure certain improvements upon the pulverizing-machine invented by me and patented to me in and by Letters Patent of the United States No. 265,791, dated October 10, 1882, to which Letters Patent reference is also to be made for the more clear comprehension of my present improvements. Among other features of construction, my above-named machine embodies two sleeve-journals, described

as of Parrott-gun form, applied to and rigidly connected with the shaft, upon the rounded breeches of which sleeve-journals the disks are seated, free to yield or rock to accommodate 5 themselves to any varying movement of the ball.

My invention also relates to and embodies in its structure certain improvements upon the wet-pulverizing machine invented by Stephen P. M. Tasker, and patented to him in and by Letters Patent of the United States No. 265,713, dated October 10, 1882, to which Letters Patent reference is also to be made for a more clear comprehension of my present improvements. Among other features of construction, Tasker's machine above named embodies the application to sleeve-journals of the character invented by me of clutch-lugs which are adapted to take into lug-seats 20 formed in the rear face of the disks, and of proper size to permit of a rocking of each disk upon its sleeve-journal with respect to the clutch-lugs, and also embodies a spring between the disks.

My invention also relates to and embodies in its structure certain improvements upon the dry-pulverizing machine invented by the said Stephen P. M. Tasker, and patented to him in and by Letters Patent of the United States No. 265,715, dated October 10, 1882, to which Letters Patent reference is also to be made for a more clear comprehension of my present improvements. Among other features of construction, Tasker's patented machine above 35 named embodies disks without blades, and radially-disposed peripheral openings.

My invention also relates to, and preferably embodies in its structure, certain improvements upon the pulverizing-machine invented by the said Stephen P. M. Tasker, and patented to him in and by United States Letters Patent No. 274,050, dated March 13, 1883, to which Letters Patent reference is also to be made for a more clear comprehension of my present 45 improvements. Among other features of construction, Tasker's patented machine above referred to embraces the provision of an improved casing and receiver for the pulverized material, the casing being supported in the 50 receiver, and the latter, embodying in its construction pedestals which support the shaft of the apparatus, embraces also an improved sleeve-journal, which is employed solely to support and actuate the disks, and not to constitute a device to assist in the journaling of the 55 shaft, the said sleeve-journals being made with straight muzzles, which are contained in stuffing-boxes applied to the screens, which simply serve as stuffing-boxes, and not as supporting 60 devices for the shaft of the machine, which latter is, as stated, journaled in and supported by the pedestals of the receiver.

Generally stated, my present invention consists in an improved means of application of 65 the disks to the sleeve-journals, whereby I am enabled to dispense with the spring between

the disks heretofore in the above-mentioned improvements necessary.

In the accompanying drawings, Figure 1 represents in central vertical longitudinal section 70 a pulverizing-machine conveniently embodying a good form of my invention, the ball or crushing-sphere and shaft being represented in elevation. Fig. 2 is a rear view of one of the disk face-plates, and Fig. 3 a rear 75 elevational view of one of the sleeve-journals.

Similar letters of reference indicate corresponding parts.

In the drawings, A represents the casing, B the receiver within which said casing is erected, C the pedestals which support the bearings for the shaft, D the shaft, E the ball-track, and F the ball or crushing-sphere. Any further description of these parts I regard as foreign 80 to the purpose of this specification.

G are the disks, which are made without blades, scoops, or take-ups, or removable bevelled bearing-plates, but which in other respects correspond to the disks described in Letters Patent No. 265,713, hereinbefore referred to. 90

K are the sleeve-journals, constructed with rounded breeches, upon which the disks seat themselves and move to accommodate the ball, and with straight muzzles of the character set forth in Letters Patent No. 274,050, hereinbefore mentioned. The central front face of each of the disks is excavated to form a circular recess, g, in which is seated an annular cushion, H, of rubber or kindred elastic material, which cushion performs the office of a spring, as hereinafter fully described.

I are the disk face-plates, of suitable dimensions to fit over the front face of the cushions in place upon the disks and fitted to the shaft. The bore of each sleeve-journal is not only conformed to the section of the central portion of the shaft, but is also provided with longitudinal channels a, in which bolts J, which retain the face-plate and cushion against the front face of the disk, are seated. The face-plate is provided with a suitable number of countersunk holes, i, in which the heads of the bolts seat themselves. The extremities of the bolts, which are threaded, pass out to the rear of the longitudinal channels in the sleeve-journals, and the nuts j, which are screwed up on the bolts to tighten them against the face-plate and cushion, are set in a socket, L, formed in the rear face of the muzzle of the sleeve-journal. It will now be readily understood that the cushions in the above-described arrangement of parts take the place of the spring between the disks heretofore necessary in the various improvements upon the Thompson device heretofore cited, and enable such rocking of the disks with respect to the sleeve-journals as is necessary to permit the ball to move on radial lines to and from the shaft, as in passing over irregular masses of material which it cannot at first crush, without permitting the ball at 130 any time to be free from the gripping action of the disks.

5 M are two convergent inclines constructed in the lower portion of the casing A, and adapted to concentrate all the material within the casing upon the ball-track, so that every particle of the material fed into the casing must eventually be acted upon by the ball and crushed between the latter and the track.

10 It is obvious that the office of the face-plates and bolts is simply that of compressing the cushions in place against the face of the disks, and that the bolts may be formed with large heads, which would seat themselves so firmly and cover such area upon the face of the cushions as to render the face-plates unnecessary.

15 Other fastening contrivances adapted to compress the cushions upon the disks, and consequently the disks upon the sleeve-journals, may be substituted for the bolts. I simply instance the face-plates and bolts as the most convenient method of securing the desired result.

Having thus described my invention, I claim—

1. In a pulverizing-machine, the combination of the disks, the sleeve-journals, the rubber cushions, and means for retaining the rubber cushions in place against the face of the disks, substantially as and for the purposes set forth. 25

2. In a pulverizing-machine, the combination of the disks, the sleeve-journals, the annular cushions, the face-plates, and the bolts, substantially as and for the purposes set forth. 30

In testimony whereof I have hereunto signed my name this 2d day of July, A. D. 1883.

HERMANN BERNHARD FELDMANN.

In presence of—

J. BONSALL TAYLOR,
JOHN JOLLEY, Jr.
